George W. Ross.

BY *Max Kee*.

ATTORNEYS

UNITED STATES PATENT OFFICE.

GEORGE WASHINGTON ROSS, OF HEALDTON, OKLAHOMA.

COMBINED CLAMP AND CONNECTION.

Application filed August 2, 1923. Serial No. 655,351.

To all whom it may concern:

Be it known that I, GEORGE W. ROSS, a citizen of the United States, and a resident of Healdton, in the county of Carter and 5 State of Oklahoma, have invented certain new and useful Improvements in Combined Clamps and Connections, of which the following is a specification.

This invention relates to a combined 10 clamp and connection for the leg sections, girts, and braces of a tubular steel tower or derrick.

The object of the invention is to provide 15 a device of this character whereby the leg sections of the tower or derrick may be firmly and securely clamped and fastened to each other and whereby the girts and braces may be organized with the legs and with each other in such manner as to produce 20 a strong and rigid tower or derrick.

Another object is to provide a device of 25 this character and having the foregoing advantages and capacities and which is at the same time extremely simple in construction and adapted to be manufactured at a comparatively slight cost from materials and by means of facilities ordinarily available.

Other objects and advantages of the invention 30 reside in certain novel features of the construction, combination and arrangement of parts which will be hereinafter more fully described and particularly pointed out in the appended claims, reference being had to the accompanying drawings forming part of this specification, and in which:

Figure 1 is a fragmentary perspective view, showing a portion of the tower or 40 derrick embodying the combined clamps and connections constituting the present invention;

Figure 2 is a detail view in perspective showing one of the combined clamps and 45 connections detached, a portion of a girt and portions of a pair of braces being also shown connected to one of the wings of the clamp member;

Figure 3 is a detail perspective view, 50 showing the inner side of the clamp member and clamping plate; and

Figure 4 is a fragmentary view in longitudinal section, illustrating how the ends of the adjacent leg sections are secured together by the device constituting the present invention.

Referring to the drawings, the numeral 10 designates the leg sections of a tower and the numeral 11 designates the girts and braces.

The combined clamps and connections which constitute the present invention are designated generally at 12 and each includes a clamping member indicated generally at 13 and which is constructed of metal and comprises a curved plate like body portion 14 shaped and formed to snugly fit up against portions of the peripheries of the ends of adjacent leg sections, as shown in Figure 4. The curved plate-like body portion 14 of each member overlaps the adjacent ends of the leg sections with which it is associated, it being sufficiently elongated for this purpose. Each body portion 14 of each clamp member 12 also has an angular extent of almost one-half of the circumference of the leg sections so as to extend approximately one-half the way around the same. Divergent wings 15 are integrally formed with each curved plate like body portion. These wings 15 are continuous with the body portion 14 but they are so related to the same that in the assembly they extend tangentially from the leg sections and at right angles to each other. Each wing 15 is provided with a series of apertures 16 for a purpose which will hereinafter appear.

A cooperating clamping plate 17 is provided and is also shaped and formed so as to be adapted to be snugly fitted against the ends of adjacent leg sections. It is to be understood that one such plate 17 is provided for each clamping member 13, the clamping plate 17 being fitted in the spaces between the divergent wings 15 and having an angular extent somewhat less than one-half of the circumference of the leg sections. However the combined angular extent of the curved plate-like body portion 14 and the clamping plate 17 is such that in the assembly two serve to practically encompass and enclose the end portions of the adjacent leg sections 10. Bolt holes 18 and 19 are provided in the curved plate-like body portion 14 and the clamping plate 17 and in the assembly are aligned with bolt holes 20 provided in the leg sections. Bolts 21 are extended through the aligned bolt holes 18, 19 and 20, the bolts having heads 22 engaging against the clamping plates 17. Nuts 23 are threaded on the ends thereof which

project beyond the body portions 14 and engage these body portions. It is obvious that the fastening means constituted by the bolts and nuts 21 and 23 not only serve to 5 urge the clamping member and clamping plate into clamping engagement with the leg sections to hold the leg sections against lateral displacement but also effectively prevents axial displacement of the leg sections 10 as well as axial displacement of the clamping member and clamping plate since the bolts of the fastening means traverse the leg sections. The girts and braces 11 are connected to the wings 15 by means of headed 15 bolts 24 and nuts 25, the bolts being extended through the openings or bolt holes 16 provided in the wings and through suitable bolt holes provided thereon in the ends of the girts and braces and the nuts being threaded 20 on the bolts 23 and engaged with the girts and braces. In this manner the wings with their openings 16 afford means whereby the girts and braces are connected with the legs.

The combined clamp and connection thus 25 provided may be readily assembled or taken down and at the same time when assembled provides for proper connection and organization for parts of the tower or derrick and produces a strong and rigid tower. At the 30 same time the combined clamp and connection is of simple and durable construction adapted for comparatively inexpensive manufacture. It is to be understood in this connection that the metal of which the 35 clamping plate and clamping member are constituted is of sufficient resiliency to enable the parts to be properly formed and shaped in manufacture and yet has sufficient strength and rigidity to enable the 40 parts to maintain their form and resist distortion in use. The clamping member together with the clamping plate practically encircle the end portions of adjacent leg sections so as to brace and reinforce the 45 same as well as to connect these parts together.

It is to be understood that with this construction any leg section can be removed and replaced without removing any of the girts 50 or braces. Moreover, the bolts passing through the leg sections will prevent the combined clamps and connections from slipping up or down, thereby obviating a serious and annoying disadvantage in devices of this 55 kind heretofore constructed.

If desired the bolt holes in the leg sections as well as in the parts 13 and 17 may be made square and the shanks of the bolts may be made square so that the bolts cannot 60 turn relative to the bolt holes, whereby tightening of the nuts on the bolts is facilitated.

A variation of this arrangement may consist in making only the bolt holes in the part 65 13 square and employing carriage bolts. that

is, bolts having square shoulders adjacent their heads but round shanks beyond said shoulders. In any event the portions of the shanks of the bolts with which the nuts coact will have to be made round.

If desired the bolt holes in the leg sections as well as in the parts 13 and 17 may be made oblong and the shanks of the bolts may be made oblong also, so that the bolts cannot turn relative to the bolt holes, whereby 75 by tightening of the nuts on the bolts is facilitated.

I claim:

1. A combined clamp and connection for the leg sections, girts and braces of a tubular steel tower or derrick comprising a clamp member having a curved plate constituting the body portion of the clamp member and adapted to be snugly fitted against the peripheries of adjacent leg sections, the curved plate overlapping the ends of adjacent leg sections, divergent wings integral with the curved plate and affording connecting means for the girts and braces, a cooperating clamping plate adapted to be fitted against the ends of adjacent leg sections in the space between the divergent wings, and fastening means for urging the clamping plate and clamping member into clamping engagement with said leg sections.

2. A combined clamp and connection for the leg sections, girts and braces of a tubular steel tower or derrick comprising a clamp member having a curved plate constituting the body portion of the clamp member and adapted to be snugly fitted against the peripheries of adjacent leg sections, the curved plate overlapping the ends of adjacent leg sections, divergent wings integral with the curved plate, each of said divergent wings being provided with a plurality of bolt holes to afford connecting means for the girts and braces, a cooperating clamping plate adapted to be snugly fitted against the ends of adjacent leg sections and the space between the divergent wing, the clamping plate and the clamp member being adapted to substantially encompass the end portions of adjacent leg sections, said clamping plate and said clamp member being provided with bolt holes and the end portions of the leg sections having bolt holes adapted to be aligned with the bolt holes of the clamping plate and clamp member in assembly and bolts and nuts for securing the clamping plate to the clamp member and to the leg sections, the bolts being extended through the aligned bolt holes.

3. A combined clamp and connection for the leg sections, girts and braces of a tubular steel tower or derrick comprising a clamp member having a curved plate constituting the body portion of the clamp member and adapted to be snugly fitted against the peripheries of adjacent leg sections, the curved

plate overlapping the ends of adjacent leg sections, divergent wings integral with the curved plate and affording connecting means for the girts and braces, a cooperating clamping plate adapted to be fitted against the ends of adjacent leg sections in the space between the divergent wings, and

fastening means for urging the clamping plate and clamping member into clamping engagement with said leg sections, said fastening means including bolts traversing the leg sections.

GEORGE WASHINGTON ROSS.
